J. A. LUNDEEN.

ELECTRICALLY OPERATED SWITCH.
APPLICATION FILED JUNE 30, 1909.

Patented July 26, 1910.

Fig. 1

UNITED STATES PATENT OFFICE.

JOHN A. LUNDEEN, OF EDGEWOOD PARK, PENNSYLVANIA.

ELECTRICALLY-OPERATED SWITCH.

965,639.

Specification of Letters Patent. Patented July 26, 1910.

Application filed June 30, 1909. Serial No. 505,209.

To all whom it may concern:

Be it known that I, JOHN A. LUNDEEN, a citizen of the United States, and a resident of Edgewood Park, in the county of Allegheny and State of Pennsylvania, have invented a new and Improved Electrically-Operated Switch, of which the following is a full, clear, and exact description.

My invention relates to electrically-operated switches, my more particular purpose being to produce a device of this kind having certain constructional advantages hereinafter described.

More specifically stated, my invention comprehends an electrically-operated lever to be connected with a valve or the like, to be actuated occasionally in one direction when one circuit is closed, and in the opposite direction when another circuit is closed.

My invention further comprehends means controllable at will for adjusting the play of the aforesaid lever.

Reference is to be had to the accompanying drawings forming a part of this specification, in which similar characters of reference indicate corresponding parts in the figures.

Figure 1 is a view partly in plan and partly in section, showing my improved controller as connected with a piston valve in such manner as to open and close the same when the various sets of magnets of the controller are energized; and Fig. 2 is a substantially vertical section upon the line 2—2 of Fig. 1, looking in the direction of the arrow and showing the means for adjusting the play of the movable lever. Fig. 3 is a diagram of the wiring.

At 3 is shown a valve cylinder and connected with it are pipes 4, 5.

At 6 is a piston which may control a supply of steam, a liquid or a gas, as the case may be, which is adapted under proper conditions to pass into the valve casing 45 through the pipe 4 and to pass out of said valve casing through the pipe 5.

At 7 is a by-pass for relieving back pressure upon the piston 6.

At 8 is a valve stem which is connected with a lever 9, this lever being mounted upon a pivot pin 10 and in electrical communication with a wire 11.

Mounted upon the lever 9 is a contact plate 12 and disposed upon opposite sides thereof are contact springs 13, 14.

At 15, 16 are posts and extending through the same are screws 17, 18. Adjacent to the posts 15, 16 are plates 19, 20 of insulating material. The wire 11 leads directly to a binding post 21 which is insulated from the base and supports a metallic plate 22 which carries the pivot pin 10 above mentioned.

Mounted upon the valve stem 8 and engaging the lever 9, is a spool 23 of bone, which is adjustable relatively to the valve stem 8 by nuts 24.

The screws 17, 18 are provided with bosses 25, 26 of bone or other insulating material, these bosses being disposed in alignment with each other and adapted to be engaged one at a time by the lever 9.

Magnets 27, 28 are disposed upon opposite sides of the lever 9, and connected with these magnets are wires 29, 30. Each of these magnets 27, 28 is provided with a copper tube 28 encircling its core. The purpose of this arrangement is to render the action of the magnet sluggish and cause the armature when attracted by these magnets to travel positively all of the distance necessary to make a complete stroke of the armature. This construction of magnet gives the armature 31 a long and positive movement.

Mounted upon opposite sides of the spool 23 are nuts 24, 24, which are threaded internally and fitted upon the valve stem 8, the latter being threaded externally for this purpose. By adjusting the nuts 24, 24, the general position of the valve piston may be controlled within certain limits, and this adjustment, it will be noted, is independent of any adjustment of the lever 9 brought about by aid of the screws 17, 18. The wire 30 is connected with a binding post 31 and the wire 29 is similarly connected with a binding post 32, these binding posts being in electrical communication with the contact springs 13, 14. The lever 9 is provided with a comparatively thick portion 31 of soft iron which serves as an armature for the two magnets.

At 33, 34 are wires which are connected with binding posts 35, 36, these binding posts communicating by aid of wires 37, 38 with the magnets 27, 28. Practically all of the parts above mentioned are supported upon a base 39 of metal, the valve cylinder 3 being integral with this base, as will be understood from Fig. 2. I do not limit myself however, to this particular construction.

At 40 is a battery and at 41 is a thermostat for closing a circuit from the battery 40 through either the wire 33 or the wire 34, as the case may be.

5 The operation of my device is as follows: The wires 11, 33 and 34 being connected with the thermostat and one or more open circuit batteries (not shown) in a manner already known in the art, the screws 17, 18, are adjusted and the device is ready for use. I will suppose that at the start the lever 9 is in the position indicated in Fig. 1 and that the action of a thermostat, or any other suitable device, completes a circuit, external to 15 the device shown in Fig. 1, from the wire 11 to the wire 34. This circuit may be traced as follows: Battery and thermostat (not shown), wire 11, armature 31, lever 9, contact plate 12, contact spring 13, binding post 31, wire 30, magnet 28, wire 38, binding post 36, wire 34, back to battery and thermostat. This energizes the magnet 28 which thereupon attracts the armature 31 and moves the lever 9 so that the contact plate 12 disengages the contact spring 13 and engages the contact spring 14. The disengagement of the plate 12 from the contact spring 13 opens the circuit just traced and this remains open for a time, owing to the condition 25 of the thermostat. Consequently, the lever 9 now remains motionless in its new position until another circuit is completed (by aid of the thermostat), this circuit being as follows: Battery and thermostat (not shown), wire 11, plate 22, armature 31, lever 9, contact plate 12, contact spring 14, binding post 32, wire 29, magnet 27, wire 37, binding post 35, wire 33, back to battery and thermostat. This circuit energizes the magnet 27 and causes it to attract the armature 31, thereby restoring the lever 9 to its original position indicated in Fig. 1. Each movement of the lever 9, by shifting the position 30 of the piston 6, opens or closes the pipe 4 which, as above stated, may be employed for admitting steam, gas or any other fluid or aeriform body into the casing 3. The movements of the piston 6 thus control communication between the inlet pipe 4 and the outlet pipe 5. In a building to be heated, for instance, the pipe 4 may admit steam into the casing 3, this steam passing out through

the pipe 5 to a heating system. If, now, the electric circuits above described be under control of a thermostat, it is obvious that changes in temperature, by affecting the thermostat, may control the supply of steam.

I do not limit myself in all instances to the exact construction shown, for the reason that equivalents for the various parts may be employed without departing from the spirit of my invention.

The operator, by turning the screws 17, 18, may adjust within reasonable limits the travel of the lever 9 and consequently the travel of the valve piston 6, which is itself separately adjusted so as to close the valve completely or partially, as desired. In doing this, he may regulate the travel of fluid through the pipes 4, 5.

The operator, by turning the nuts 24 and thus adjusting the spool 23 relatively to the stem 8, may to some extent control the position of the valve relatively to its casing and may do this to some extent independently of the adjustment of the screws 17, 18.

Having thus described my invention, I claim as new and desire to secure by Letters Patent:

The combination of a base, a valve casing mounted thereupon, a valve mounted within said casing and slideable in a direction coaxial therewith, a stem for said valve, a head carried by said stem, a lever connected with said head, means for adjusting said lever relatively to said stem for the purpose of affecting the stroke of said valve, said lever being provided with a portion serving as an armature, a pair of magnetic members for retracting said armature and thereby actuating said lever, a pair of contacts to be opened and closed by movements of said lever, connections from said contacts to said magnetic members for enabling said contacts to control said magnetic members, and means controllable at will for regulating the play of said lever.

In testimony whereof I have signed my name to this specification in the presence of two subscribing witnesses:

JOHN A. LUNDEEN.

Witnesses:

H. E. CARMACK,
ELIZABETH F. CARMACK.
